UNITED STATES PATENT OFFICE

164,358

CONCRETE MIXER OR ANALOGOUS ARTICLE

John P. Faber, Dunellen, N. J., assignor to Muller Machinery Company, Inc., Metuchen, N. J., a corporation of New Jersey

Application April 27, 1949, Serial No. 2,299

Term of patent 14 years

(Cl. D14—3)

To all whom it may concern:

Be it known that I, John P. Faber, a citizen of the United States, residing in the city of Dunellen, county of Middlesex, and State of New Jersey, have invented a new, original, and ornamental Design for Concrete Mixer or Analogous Article, of which the following is a specification, reference being had to the accompanying drawing, forming a part hereof.

Fig. 1 is a front perspective view of a concrete mixer, showing my design; and

Fig. 2 is a rear perspective view thereof.

I claim:

The ornamental design for a concrete mixer or analogous article, substantially as shown.

JOHN P. FABER.
